Letters Patent No. 74,539, dated February 18, 1868.

IMPROVEMENT IN HORSE-SHOES.

The Schedule referred to in these Letters Patent and making part of the same.

TO ALL WHOM IT MAY CONCERN:

Be it known that I, N. W. H U B B A R D, of the city, county, and State of New York, have invented a new and useful Improvement in Horse-Shoes; and I do hereby declare that the following is a full, clear, and exact description thereof, which will enable others skilled in the art to make and use the same; reference being had to the accompanying drawings, forming part of this specification, in which—

Figure 1 is a plan view of my improved horse-shoe.

Figure 2 is a sectional view of the same, through the line *x x*, fig. 1.

Figure 3 is a plan view of a modification of the same.

Figures 4 and 5 are corresponding views of the wrench.

Similar letters of reference indicate corresponding parts.

The object of this invention is to provide a horse-shoe with removable calks, whereby the same may be renewed from time to time, as the calks become worn, without removing the shoe from the horse's foot. It consists, in general terms, of removable plates, serving as matrices for the calks, and which are held to the shoe by screws employed in contact with certain flanges or upset edges of the plates, together with other devices, perfecting the whole, as will hereinafter be more fully set forth.

In the accompanying plate of drawings, the shoe proper is shown at A. The heel-calks are affixed to the shoe by means of heel-plates B and C. These plates have upset or vertical sides, which are dove-tailed into the shoe, as shown at B, or are simply let in flush in the outer and inner sides of the shoe, as shown at C. When dove-tailed in, a short set-screw, *b*, suffices to hold, but when merely let in, a screw, passing through from side to side, as shown at *d*, is preferable. The calks are set into these heel-plates in the same manner as the calks of the toe-plate, which will be hereinafter described. The toe-plate G is turned up in front, as shown at *f*, and bevelled to fit a corresponding bevel on the shoe, as shown at *i*, which serves, in connection with the clamp-screw *a*, to hold the plate G tightly in place. The flange *f* is recessed, so as to conform to the base of the tip *h*, which latter rests against the outside of the hoof. The clamp-screw *a* works in a rear projection of the plate G, the said projection rising from the said plate to a position behind the toe part of the shoe, so that screw *a* shall bear against the upper surface of the said toe-part, in the manner shown. A recess is made in the shoe at this period to receive the end of the clamp-screw *a*, and thereby present a surface for the said end to abut against, so that when the said screw is turned in, the bevelled parts *i* will be drawn in close contact, and the plate G be actuated to a strong, close contact with the shoe. The clamp-screw *a* also projects over the shoe, which holds the plate from being withdrawn downward. The calks E are pyramidal pieces of steel or case-hardened iron, and fit into the plates G, B, and C, substantially as shown, and, as the base of the calks is in firm contact with the bottom surface of the horse-shoe, and the sides of the holes conform to the taper of the sides of the calk, the latter is held immovably in place, and will not become loose by the most severe usage to which a shoe is subjected.

When, in the course of continued use, the parts of the calks become dulled, the plate G is removed, and new calks set in. These can be manufactured by the quantity at a trifling expense per dozen. As the holes or matrices into which they fit are made of the exact form and size of the calks, any of the latter can be taken indiscriminately and inserted.

A modification of the mode of attaching the plate C is shown at fig. 3, where the clamp-screw is within the part D, as first described, but the taper projection *j* from the horse-shoe serves, with the recess in the flanges *f* and clamp-screw, to hold the plate G firmly.

When the plate is to be removed, the clamp-screw is loosened just sufficiently to allow the point of the plate G to drop, and thereby permit the passage of the said recess by the tip *h*. The plate G is then turned laterally until clear of the tip *h* and projection *j*, when the plate can be withdrawn.

The plate is again put on by following the reverse of the above description for taking off.

The wrench, shown at figs. 4 and 5, is employed to remove the plates with. By this last modification, a smaller clamp-screw can be used than that necessary in the first-described shoe.

This invention supplies a long-felt want, and has been proved by practical trial to be durable and perfectly effective in preventing horses from slipping on ice or frosted pavements.

Having described my invention, I claim as new, and desire to secure by Letters Patent—

1. The removable toe-calks E for horse-shoes, substantially as shown and described, in combination with the toe-plate G, clamp-screw α , or its equivalent, all as and for the purpose set forth.

2. The heel-calks for horse-shoes, substantially as shown and described, in combination with the plates, as shown at B or C, and screws b or d , all as and for the purpose set forth.

The above specification of my invention signed by me, this 27th day of January, 1868.

N. W. HUBBARD.
